(57) **CLAIM**

The ornamental design for a combination outdoor ventless fireplace and brick oven, as shown and described.

DESCRIPTION

FIG. 1 is a top perspective view of a combination outdoor ventless fireplace and brick oven;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a right side elevational view thereof.

A left side elevational view is not shown because it is a mirror image to the right side elevational view shown in FIG. 6.

The broken lines depict environment that forms no part of the claimed design.

1 Claim, 4 Drawing Sheets
